UNITED STATES PATENT OFFICE.

ARTHUR C. JACKSON, OF PHILADELPHIA, PENNSYLVANIA, ASSIGNOR TO THE YALE & TOWNE MANUFACTURING COMPANY, OF STAMFORD, CONNECTICUT, A CORPORATION OF CONNECTICUT.

SEALED PADLOCK.

Application filed November 17, 1925. Serial No. 69,649.

One object of my invention is to provide a padlock with a seal which will engage the bolt and other interior mechanisms of the lock.

5 A further object of my invention is to seal the key opening of the lock as well as the interior mechanism of the lock. I lay no claim to the key hole sealing construction alone.

10 In the accompanying drawing:

Fig. 1 is a perspective view of a padlock illustrating my invention;

Fig. 2 is a sectional view with one of the side plates removed, showing the sealing 15 band engaging the bolt and the key in position;

Fig. 3 is a view similar to Fig. 2, showing the bolt withdrawn and the shackle raised; and

20 Fig. 4 is a sectional view illustrating a modification of the invention.

The mechanism of the lock may be modified without departing from the main features of the invention.

25 The casing 1 of the padlock, in the present instance, consists of a back-plate 3 made integral with the shell 4, and a front plate 2 secured to the shell by riveting.

The shackle 5 is pivoted at 6 to the casing 30 and has a perforated nose 7, into which is projected the bolt 8, having a stump 9 which extends into a slot 10 in the tumbler 11. This tumbler 11 is slotted as shown for the reception of the pin 12, and has a curved 35 extension 13 which encircles the key-way.

When the padlock is locked, the key 14 can be inserted in the key opening and mounted on the key-post 15. The key is free to turn and engage the bolt, withdrawing it and at the same time raising the tumbler 11 to such a position as to bring the extension 13 into the path of the key as shown in Fig. 3, so that it is impossible to withdraw the key when the lock is open. 40 This lock is particularly adapted for use as a railway switch lock.

The particular lock shown and as above described is fully set forth and claimed in the patent granted to Frank Soley on the 50 26th day of April, 1910, No. 956,213.

At the front of the lock is a plate 16, having a key opening 17 in line with the key opening of the lock. The plate has a slot 18 wider than the key opening for the re-

ception of the metallic sealing band 19, so 55 that when the band is in position, the key opening in the lock is closed.

In order to increase the security of the lock, the front and back-plates of the lock are slotted at 20. The bolt 8 is notched at 60 21 and the tumbler 11 is preferably notched at 22.

The notches 21 and 22 are in alignment with the slots 20 when the shackle is closed and locked, so that the metallic sealing band 65 19 can be passed through the slots in the casing as shown in Fig. 1, and through the slot 18 in the plate 16. The two ends of the band 19 are brought together under the lock and a seal 23 applied as shown in Fig. 1. 70

By this means, the key opening is not only sealed, but the sealing band prevents the movement of the bolt and other mechanism of the lock, should an endeavor be made to throw the bolt by striking or otherwise 75 manipulating the casing.

As soon as the seal is broken, the band is removed, releasing the bolt and allowing a clear passage for the key, which, when turned, withdraws the bolt and releases the 80 shackle.

In some instances the sealing band may be applied as in Fig. 4. The band 19^a is passed through the space enclosed by the shackle, after which the seal is applied. 85 By this means, the bolt and tumbler are sealed.

I claim:

1. The combination in a padlock, of a casing having slotted front and back plates; 90 a slotted locking-bolt and a slotted tumbler, the slots in said locking-bolt and tumbler being in line with the slots in the casing when the bolt is in the locking position; and a sealing band extending through the 95 casing slots and engaging the bolt and the tumbler.

2. The combination in a padlock, of a casing having slotted front and back plates; 100 a notched bolt, the notch in the bolt aligning with the slots in the casing when the bolt is in locked position; a slotted plate at the key-hole of the lock; and a sealing band extending through the slot in the casing and engaging the bolt and through the slot in 105 the plate and covering the key-hole of the lock.

ARTHUR C. JACKSON.
